HANGING FLORAL CONTAINER

Jack W. Barbeau, 19108 44th W., Lynnwood, Wash.

Filed Sept. 17, 1962, Ser. No. 71,738

Term of patent 14 years

(Cl. D35—3)

I claim:

The ornamental design for a hanging floral container, as shown.
